UNITED STATES PATENT OFFICE

2,473,399

ELECTRON DISCHARGE DEVICE OF THE
MAGNETRON TYPEPercy L. Spencer, West Newton, Mass., assignor
to Raytheon Manufacturing Company, Newton,
Mass., a corporation of Delaware

Application March 27, 1945, Serial No. 585,025

12 Claims. (Cl. 315—40)

1

My present invention relates to electron-discharge devices, and more particularly to electron-discharge devices of the so-called magnetron type, which are adapted to generate electrical oscillations having a wave length of the order of a few centimeters, or less.

One of the objects of my present invention is to provide an anode structure for a magnetron, which is of such design as to enable building said magnetron of sufficient size to generate appreciable power and, at the same time, maintain the wave length of the output thereof within the limits above referred to.

Another object of my present invention is to enable the attainment of the foregoing object in a simpler manner than has heretofore been possible.

These and other objects of my present invention, which will become more apparent as the detailed description thereof progresses, are attained, briefly, in the following manner:

I so construct the electron-discharge device of my present invention as to include an anode structure, preferably, in the form of a cylindrical body provided with a plurality of interiorly-extending, radially-disposed anode members. Said anode members are of such size that each alternate pair thereof, together with that portion of said cylindrical body lying therebetween, constitute a resonant line at a frequency, for example, lower than that desired on the final output of the device.

I connect each intermediate pair of said anode members, at points along their length, with a low-impedance member, whereby the inner portions of adjacent anode members so connected, together with said low-impedance member, likewise constitute a resonant line, but at a frequency, for example, higher than that desired of said final output.

It will be observed that a portion of each of the connected anode members is common to two differently-dimensioned resonant lines, and this is preferred construction.

I have found that by building the device as above, the output thereof includes appreciable power of a wave length which is the average of the wave lengths of the two differently-dimensioned resonant lines formed in the anode structure.

In the accompanying specification I shall describe, and in the annexed drawings show, an illustrative embodiment of the electron discharge device of my present invention.

In the drawings,

2

Fig. 1 is a longitudinal sectional view taken substantially through the center of an electron-discharge device made in accordance with my present invention; and

Fig. 2 is a transverse sectional view taken along line 2—2 of Fig. 1.

Referring now more in detail to the aforesaid illustrative embodiment of my present invention, and with particular reference to the drawings illustrating the same, the numeral 5 generally designates an electron-discharge device of the magnetron type. Such a device includes an anode structure 6, a cathode structure 7, and magnetic means 8 for establishing a magnetic field in a direction perpendicular to the path of the electron-flow between said cathode and anode structures.

The anode structure 6 comprises, preferably, a hollow cylindrical body 9, made of highly conductive material, such as copper, and having its interior provided with an annular boss 10 from which extends a plurality, here shown as sixteen, of interiorly-extending radially-disposed anode members in the form of vanes 11.

Each alternate pair of adjacent anode members, together with that portion of the boss 10 of the cylindrical body 9 lying therebetween, constitute a resonant line, for example, at a frequency which is lower than that desired of the final output of the device.

The adjacent anode members 11 of each intermediate pair thereof are connected, at points located along their length, said locations depending upon the frequency desired of the second of the above referred to resonant lines, by a low-impedance member 12, for example, a conducting strap, whereby each such connected pair of anode members, together with the low-impedance member therebetween, constitute, respectively, each of said second resonant lines. The dimensions of said second resonant lines may be such that each is resonant at a frequency which is higher than that desired of the final output of the device.

While not limited thereto, it is preferred, in the interest of simpler manufacturing technique, that each of the anode members 11 be provided, in their upper and lower edges, with slots 13, in which, initially, conducting rings may be secured. Subsequently, those portions of such rings as connect the adjacent anode members 11 of alternate pairs thereof can be removed, leaving the straps 12, and thereby forming the two differently-dimensioned resonant lines above described.

55 The anode structure 6 is closed at its ends, for

example, by end plates 14 and 15, the junctions between the cylindrical body 9 and said plates 14 and 15 being hermetically sealed, as at 16.

The cathode structure 7, which is coaxial with the anode structure 6, may include a highly electron-emissive, oxide-coated sleeve 17, adapted to be heated by a filament (not shown) having terminals 18 and 19 electrically connected to lead-in conductors 20 and 21, the latter being, in turn, connected to an appropriate, external source of E. M. F. (not shown). Said lead-in conductors may enter the device through glass seals 22 and 23, fused into pipes 24 and 25, threadedly engaged and hermetically sealed in the cylindrical body 9.

Mounted in any preferred manner, immediately adjacent the end plates 14 and 15, is a pair of pole pieces 26 and 27, said pole pieces being disposed, as previously indicated, to establish a magnetic field in a direction perpendicular to the path of the electron-flow between the cathode structure 7 and anode structure 6.

In order to extract power from the device, I may, for example, introduce a loop 28 into the space between any two of the anode members 11 forming the longer of the aforementioned resonant lines, said loop being connected to a conductor 29, embedded in a glass seal 30 fused into the outer end of a pipe 31, in turn, threadedly engaged and hermetically sealed in the cylindrical body 9 of the anode structure.

Now, by suitably heating the cathode of the device, and applying a proper potential difference between said cathode and the anode, the device will generate electrical oscillations of frequencies determined, primarily, by the distributed capacitances and inductances built into the same as a function of the geometry thereof, more especially, of the dimensions of the elements making up the aforementioned resonant lines.

It will be found that, while the device oscillates at wave lengths corresponding to the two differently-dimensioned resonant lines incorporated therein, there will be present, in the output thereof, appreciable power of a wave length corresponding to the average of the wave lengths of said differently-dimensioned lines, and the latter may be extracted, for example, by an appropriately tuned circuit 32.

This completes the description of the aforesaid illustrative embodiment of my present invention. It will be noted from all of the foregoing that I have provided an electron-discharge device of the magnetron type, which includes an anode structure so designed that, although the output of the device is of very short wave length, the device as a whole may be of substantial size, thus permitting the generation of appreciable power. It will also be noted that the design of the device is simple, and is such as to enable its relatively easy manufacture.

Other advantages of my present invention will readily occur to those skilled in the art to which the same relates.

What is claimed is:

1. An electron-discharge device comprising: an anode structure provided with a plurality of anode members; at least one pair of said anode members, together with at least a portion of the anode structure lying therebetween, being electrically effective to constitute a first, shorted transmission line of predetermined dimensions adapted to resonate at a first, predetermined wave length; a low-impedance member connecting at least one pair of said anode members at points intermediate

the length thereof; a portion of each of said connected anode members, together with said low-impedance member, being electrically effective to constitute a second, shorted transmission line of different dimensions than said first-named transmission line and adapted to resonate at a second, predetermined wave length; and an output circuit, tuned to the average of the resonant wave lengths of said first and second transmission lines, coupled to at least one of said transmission lines.

2. An electron-discharge device comprising: an anode structure provided with a plurality of anode members; at least one pair of said anode members, together with at least a portion of the anode structure lying therebetween, being electrically effective to constitute a first, shorted transmission line of predetermined dimensions adapted to resonate at a first, predetermined wave length; a conductive strap connecting at least one pair of said anode members at points intermediate the length thereof; a portion of each of said connected anode members, together with said strap, being electrically effective to constitute a second, shorted transmission line of different dimensions than said first-named transmission line and adapted to resonate at a second, predetermined wave length; and an output circuit, tuned to the average of the resonant wave lengths of said first and second transmission lines, coupled to at least one of said transmission lines.

3. An electron-discharge device comprising: an anode structure provided with a plurality of interiorly-extending, radially-disposed anode members; at least one pair of adjacent anode members, together with at least a portion of the anode structure lying therebetween, being electrically effective to constitute a first, shorted transmission line of predetermined dimensions adapted to resonate at a first, predetermined wave length; 35 and a low-impedance member connecting at least one pair of adjacent anode members at points intermediate the length thereof; a portion of each of said connected anode members, together with said low-impedance member, being electrically effective to constitute a second, shorted transmission line of different dimensions than said first-named transmission line and adapted to resonate at a second, predetermined wave length.

4. An electron-discharge device comprising: an anode structure provided with a plurality of interiorly-extending, radially-disposed anode members; at least one pair of adjacent anode members, together with at least a portion of the anode structure lying therebetween, being electrically effective to constitute a first, shorted transmission line of predetermined dimensions adapted to resonate at a first, predetermined wave length; and a conductive strap connecting at least one pair of adjacent anode members at points intermediate the length thereof; a portion of each of said connected anode members, together with said strap, being electrically effective to constitute a second, shorted transmission line of different dimensions than said first-named transmission line and adapted to resonate at a second, predetermined wave length.

5. An electron-discharge device comprising: an anode structure provided with a plurality of anode members; at least one pair of said anode members, together with at least a portion of the anode structure lying therebetween, being electrically effective to constitute a first, shorted transmission line of predetermined dimensions adapted to resonate at a first, predetermined wave length; 70 and a low-impedance member connecting at least one

pair of said anode members at points intermediate the length thereof, whereby a portion of each of said anode members so connected is common to said first transmission line and to a second, shorted transmission line of different dimensions; said portions of each of said connected anode members, together with said low-impedance member, being electrically effective to constitute said second, shorted transmission line, which is adapted to resonate at a second, predetermined wave length; and an output circuit, tuned to the average of the resonant wave lengths of said first and second transmission lines, coupled to at least one of said transmission lines.

6. An electron-discharge device comprising: an anode structure provided with a plurality of anode members; at least one pair of said anode members, together with at least a portion of the anode structure lying therebetween, being electrically effective to constitute a first, shorted transmission line of predetermined dimensions adapted to resonate at a first, predetermined wave length; a conductive strap connecting at least one pair of said anode members at points intermediate the length thereof, whereby a portion of each of said anode members so connected is common to said first transmission line and to a second, shorted transmission line of different dimensions; said portions of each of said connected anode members, together with said strap, being electrically effective to constitute said second, shorted transmission line, which is adapted to resonate at a second, predetermined wave length; and an output circuit, tuned to the average of the resonant wave lengths of said first and second transmission lines, coupled to at least one of said transmission lines.

7. An electron-discharge device comprising: an anode structure provided with a plurality of interiorly-extending, radially-disposed anode members; each alternate pair of adjacent anode members, together with that portion of said anode structure lying therebetween, being electrically effective to constitute a first, shorted transmission line of predetermined dimensions adapted to resonate at a first, predetermined wave length; and a low-impedance member connecting each intermediate pair of adjacent anode members at points intermediate the length thereof, whereby a portion of each of said anode members so connected is common to one of said first transmission lines and to a second, shorted transmission line of different dimensions; said portions of each of said connected anode members, together with said low-impedance member, being electrically effective to constitute said second, shorted transmission line, which is adapted to resonate at a second, predetermined wave length.

8. An electron-discharge device comprising: an anode structure provided with a plurality of interiorly-extending, radially-disposed anode members; each alternate pair of adjacent anode members, together with that portion of said anode structure lying therebetween, being electrically effective to constitute a first, shorted transmission line of predetermined dimensions adapted to resonate at a first, predetermined wave length; and an arcuate conductive strap connecting each intermediate pair of adjacent anode members at points intermediate the length thereof, whereby a portion of each of said anode members so connected is common to one of said first transmission lines and to a second, shorted transmission line of different dimensions; said portions of each of said connected anode members, together with

said strap being electrically effective to constitute said second, shorted transmission line, which is adapted to resonate at a second, predetermined wave length.

5 9. An electron-discharge device comprising: an anode structure provided with a plurality of interiorly-extending, radially-disposed anode members; each alternate pair of adjacent anode members, together with at least a portion of the anode structure lying therebetween, being electrically effective to constitute a first, shorted transmission line of predetermined dimensions adapted to resonate at a first, predetermined wave length; a low-impedance member connecting each intermediate pair of adjacent anode members at points intermediate the length thereof; a portion of each of said connected anode members, together with said low-impedance member, being electrically effective to constitute a second, shorted transmission line of different dimensions than said first-named transmission line and adapted to resonate at a second, predetermined wave length; and an output circuit, tuned to the average of the resonant wave lengths of said first and second transmission lines, coupled to at least one of said transmission lines.

15 10. An electron-discharge device comprising: an anode structure provided with a plurality of interiorly-extending, radially-disposed anode members; each alternate pair of adjacent anode members, together with that portion of said anode structure lying therebetween, being electrically effective to constitute a first, shorted transmission line of predetermined dimensions adapted to resonate at a first, predetermined wave length; a low-impedance member connecting each intermediate pair of adjacent anode members at points intermediate the length thereof, whereby a portion of each of said anode members so connected is common to one of said first transmission lines and to a second, shorted transmission line of different dimensions; said portions of each of said connected anode members, together with said low-impedance member, being electrically effective to constitute a second, shorted transmission line of different dimensions than said first-named transmission line and adapted to resonate at a second, predetermined wave length; and an output circuit, tuned to the average of the resonant wave lengths of said first and second transmission lines, coupled to at least one of said transmission lines.

20 11. An electron-discharge device comprising: an anode structure provided with at least three adjacent anode members; one of the outer and the intermediate of said anode members, together with that portion of said anode structure lying therebetween, being electrically effective to constitute a first, shorted transmission line of predetermined dimensions adapted to resonate at a first, predetermined wave length; and a low-impedance member connecting the remaining outer and said intermediate anode members at points intermediate the length thereof; a portion of said connected anode members, together with said low-impedance member, being electrically effective to constitute a second, shorted transmission line of different dimensions than said first-named transmission line and adapted to resonate at a second, predetermined wave length.

25 12. An electron-discharge device comprising: an anode structure provided with at least three adjacent anode members; one of the outer and the intermediate of said anode members, together with that portion of said anode structure lying

therebetween, being electrically effective to constitute a first, shorted transmission line of predetermined dimensions adapted to resonate at a first, predetermined wave length; and a conductive strap connecting the remaining outer and said intermediate anode members at points intermediate the length thereof; a portion of said connected anode members, together with said strap, being electrically effective to constitute a second, shorted transmission line of different dimensions than said first-named transmission line and adapted to resonate at a second, predetermined wave length.
